UNITED STATES PATENT OFFICE.

GEORGE F. ROSE, OF NEW YORK, N. Y.

FRAME CONSTRUCTION FOR TYPE-WRITERS.

1,219,159.

Specification of Letters Patent. Patented Mar. 13, 1917.

Application filed May 29, 1914. Serial No. 841,701.

To all whom it may concern:

Be it known that I, GEORGE F. ROSE, a citizen of the United States, residing at the city of New York, borough of Manhattan, county and State of New York, have invented a certain new and useful Frame Construction for Type-Writers, of which the following is a specification.

This invention is a frame construction for typewriters, the same being intended for use, more particularly, in connection with machines of the so-called "front strike" portable variety, although it is apparent that the invention, or parts thereof, may be used, and to good advantage, in connection with other varieties of machines.

The object in view is to secure precision and accuracy in the assemblage of the several mechanisms, to expedite the work of assemblage, to save time and labor in the performance of the necessary work, and to obtain lightness of weight the whole tending to ultimately effect economy of manufacture.

Generally speaking, it has been and is now the custom to employ cast metal frame constructions, and to resort to separate brackets, or equivalent mechanical devices, which require care, skill, time and labor to effect the assemblage with precision and accuracy. These are obviated by my invention to such an extent that the time of the workman in assembling the parts with precision and accuracy is materially economized.

One feature of my invention is a frame for supporting or carrying the working parts of the machine, said frame being separate from an outside or main frame and positioned interiorly thereof, whereby all the parts may be positioned on the first named frame and the latter may be handled or manipulated at the will of the workman prior to the assemblage of the inside frame and the working parts within the exterior frame, the latter being of a finished or ornamental character.

A salient feature of the interior frame is a sheet metal construction so bent and ribbed as to possess great stiffness and strength to prevent buckling or distortion thereof and all parts of which are integral so that the working devices, such as the ribbon mechanism, the type bar brackets, the key lever brackets, etc., may be assembled with accu-

racy, precision and the least amount of labor on the part of the workman.

Other features of the invention are a stamped metal front plate forming an element of the interior frame and attachable therewith to the exterior frame, and a sector plate attachable to said interior frame, said front plate and the sector plate each consisting of a single stamping which is stayed and braced to impart the required stiffness and rigidity thereto.

Other features and advantages of the invention will be apparent from the following detailed description.

In the drawings:

Fig. 1 is a plan view of a sheet metal stamping adapted to form the interior frame for supporting the working parts of a typewriting machine.

Fig. 2 is a top plan view of the interior frame formed from the blank or stamping of Fig. 1 by bending the latter to the required form.

Fig. 3 is a plan view of the metal stamping which constitutes the front plate of the interior frame.

Fig. 4 is an edge elevation of the front plate formed by bending up the stamping shown in Fig. 3.

Fig. 5 is a plan view of a sheet metal sector plate.

Fig. 6 is a cross section of the sector formed by bending the stamping of Fig. 5.

Fig. 7 is a plan view illustrating the interior frame secured within an outer frame or casing in accordance with this invention.

Fig. 8 is a central vertical section of the parts shown in Fig. 7.

The stamping or blank shown in Fig. 1 comprises a plate A and wings B, C, the whole being cut in one piece from sheet metal, such as sheet steel, sheet brass, or like material. The wings B, C are foldable into parallel relation, the lines of the fold being indicated at a. The plate A is foldable on the lines b, c for the purpose of producing flanges, one of which is indicated at b' in Fig. 2, said flanges imparting the desired rigidity and stiffness to the plate so as to preclude buckling or distortion thereof. Said plate A is cut out or slotted at d, e, and while the metal is entirely removed from the slot d, yet in the slot e sufficient metal is left to produce tongues D, the latter being foldable in a direction rear-

wardly of the plate and on the lines indicated at a' , whereby the rearwardly extending tongues D are adapted to form brackets for supporting certain parts of the automatic ribbon reverse mechanism entering into the construction of the typewriting machine.

The top edge of plate A is curved at a^2 , whereas the bottom edge extends in a straight line, as at a^3 , except at the end portions of the plate, at which end portions the bottom edge is curved or inclined, as at a^4 . The top edge a^2 of plate A is curved to produce fillets at a^5 , and intermediate these fillets the plate A is provided with an arm E and a longer arm F, the latter being provided at its free end with an extension G. The arm E is bent at a right angle to the plane of the plate A so as to extend rearwardly thereof and form a bracket for supporting a reversing lever of the ribbon mechanism, the latter forming one of the working parts of the machine. Said arm F is foldable on the dotted line f and in a direction to extend rearwardly of plate A, after which the arm is bent to produce an inwardly extending lug G which serves as a guide for a rod of the ribbon reverse mechanism, said arm F constituting a support for the spring barrel by which movement is imparted to the platen carriage of the typewriting machine.

The stamping is provided with cut-outs h near the lower edge and with inwardly extending slots i near the upper edge. The wings B C are formed with inwardly extending arms H positioned below the cut-outs h, said arms H being foldable on the line h'. The upper corners of plate A are provided with extensions I, the lower edges of which are bounded by one wall of the slots i, and these extensions are foldable on the lines i'. The plate is provided at its top edge above the fillets a^5 with further extensions J', having the peculiar shape shown more particularly in Fig. 1, and intermediate the extensions I J' are the notched lugs L. Said notched lugs L are foldable on the dotted lines l so that when the top edge a^2 of the plate is folded on the line b so as to form the flange, the lugs L will extend rearwardly from the plate, as shown in Fig. 2, whereby said parts L serve as guides for the rods or stems attached to the platen carriage and forming a part of the carriage shifting mechanism. The fillets or offsets a^5 are bent rearwardly to form brackets for parts of the ribbon mechanism.

The extension J' at the right hand side of the plate is slightly offset to hold certain parts of the ribbon vibrator mechanism. The parts of these two extensions J' below the dotted line j remain in the same plane as plate A.

In addition to the slots heretofore de-

scribed, the plate is provided with slots o which produce tongues O, the latter being foldable on the dotted line o', so that the tongues extend forwardly with respect to the plate and serve the purpose of brackets for the attachment of the space keys.

When the wings B C are folded on the lines a so that they extend parallel to each other and at right angles to plate A, it is apparent that the arms H and D are foldable with said wings B C, whereas the other arms I at the upper corners of the plate remain in the plane of the plate. Now when the arms H are folded with the wings they extend at a right angle to the arms I, but by folding said arms H at a right angle to the wings B C, said arms H are in the same plane with the arms I, whereby the arms H I are adapted to serve as means for fastening the interior frame to an exterior frame or casing. In this connection it is noted that the free ends of the arms are bent on the dotted lines h' i' so as to form flanges adapted for the passage of screws, whereby the interior frame member may be secured firmly in position to the exterior frame or casing.

The wings B C are provided at their forward edges with lugs b² foldable on the line b³ so that the lugs are positioned for attachment to the front plate, to be presently described, and, furthermore, each wing is provided with an additional lug b⁴ foldable into a horizontal position so as to be available for the attachment of a certain part of the ribbon reverse mechanism.

From the foregoing description it will be seen that the single blank or stamping is cut in such a form as to constitute the entire inner frame, said stamping or blank being provided with flanges for stiffening or imparting rigidity to the frame, with means for the attachment of said interior frame to an outer frame or casing, and with a number of lugs, brackets, or flanges for mounting certain parts of the various mechanisms which enter into the construction of the machine, thus reducing the labor of the workman in assembling the working parts in positions requiring precision and accuracy. The production of the entire blank is accomplished by the operation of a single die and subsequent to the stamping of said blank it is bent at definite lines and in various directions so as to result in a complete inner frame.

Associated with the inner frame is a front plate P, shown more particularly in Figs. 3 and 4, and assembled with the one-piece inner frame in an operative position within an outer frame or casing, as shown in Figs. 7 and 8. This front plate is provided with a series of steps p and with a like series of notches p' in its top edge, the latter extending in a general curved direction. Fur-

thermore, the front plate is foldable on the dotted line p^2 so as to produce an offset p^3 , shown in dotted lines in Fig. 4, and said lower edge of the front plate is formed with a series of notches p^4 , three of which are indicated in full lines and the remaining notches are indicated diagrammatically by the single lines. At its ends the front plate is provided with extensions p^5 adapted to be folded at right angles to the plate so as to form lugs which are adapted for engagement with the inner surfaces of the outer frame or casing. This front plate is cut or stamped in the required form by one operation of a suitable die, and subsequent to the production of the plate its extensions p^5 are bent to form the lugs through which are adapted to pass screws for attaching said front plate to the exterior frame. The front plate extends across the open space between the wings B C of the interior frame, and the lugs b^2 on the wings of said interior frame engage with one face of the front plate and are fastened thereto in any suitable way, as for example by screws. It is apparent that the stepped edges p and the notches p^4 thereof will position with precision and accuracy the brackets for the angle levers employed between the type bars and key levers, whereas the notches p^5 in the lower edge of the front plate serve as guides for the key levers of the typewriting machine.

In Figs. 5 and 6 there is shown a sector plate Q to which is adapted to be attached the brackets on which the key levers are hung, said sector plate being positioned in rear of the front plate. The sector plate is cut or stamped from a single piece of sheet metal and the operation of cutting and perforating this plate will distort or buckle it notwithstanding extreme care in the stamping operation. To overcome this tendency of the metal plate to buckle, I bend it along the lines q so as to produce flanges q' , the operation of bending which flanges effectually straightens the plate so that it remains in a true and straight condition. The sector is provided at its end with attaching flanges q^2 , and at its bottom edge with a lug q^3 , the latter being bendable at right angles to the plane of the plate, whereas the flanges q^2 lie in the plane of the plate, although the flanges may be bent up to impart stiffness thereto.

R designates an exterior frame which is struck up from a single piece of sheet metal so as to form the back, sides and front, said sides having the form shown more particularly in Fig. 8. The frame is provided on its edges with the inwardly extending flanges r , but at the front of the frame the top edges thereof are curled over at r' in order to impart the desired finish to said frame.

In addition to the flanges r the sides of the frame are provided with one or more depressions or panels r^2 , said flanges and panels operating to impart the desired stiffness and rigidity to the outer frame.

It will be seen that the interior frame, the front plate and the sector plate are produced rapidly and economically by simply stamping the parts from sheet metal of the required gage and strength, after which the interior frame, the front plate and the sector plate are adapted to be assembled and fastened in the required accurate position without undue care on the part of the workman. The exterior frame R is of the usual ornamental character and if it is handled from the beginning to the end of the operation of assembling the working parts, the finish of this frame is marred and soiled by the hands of the workman. According to my invention, however, all the operating parts are assembled on the interior frame, after which said interior frame with the working parts and the plates P and Q are brought together and fastened within the exterior frame, thus saving the operations of handling the exterior frame, except upon the final assemblage of the machine. It is apparent that the exterior frame is composed of sheet metal cut or stamped in the required form and bendable so as to produce the sides, front and rear, the required stiffness and rigidity in the exterior frame being obtained by the provision of the flanges r .

Having thus fully described the invention, what I claim as new, and desire to secure by Letters Patent is:

1. In a frame construction for typewriters, a frame member formed by a metal stamping comprising an unbroken solid back plate and a plurality of wings bendable into substantially parallel relation to each other and at a right angle to the back plate, said metal stamping being slotted inwardly from the edges thereof and producing members adapted to be bent relatively to the metal stamping, which bent members are adapted to form brackets whereby the frame member resulting from the metal stamping is adapted to be fastened to an exterior machine frame.

2. In a frame construction for typewriters, a frame member formed from a metal stamping comprising a back plate and a plurality of wings bendable into substantially parallel relation to each other and at a right angle to the back plate, said back plate being provided with an integral bracket for a ribbon vibrator.

3. In a frame construction for typewriters, a frame member formed from a metal stamping comprising a back plate and a plurality of wings bendable into substantially parallel relation to each other and

- at a right angle to the back plate, said back plate being provided with integral lugs extending forwardly from said back plate and positioned for supporting the space key devices.
4. In a frame construction for typewriters, a frame member formed from a metal stamping comprising a back plate and a plurality of wings bendable into substantially parallel relation to each other and at a right angle to the back plate, said wings being provided with lugs for supporting parts of a ribbon reverse mechanism.
5. In a frame construction for typewriters, a frame member comprising a flanged plate having integral therewith two wings bendable into substantially parallel relation to each other, said plate being provided with a ribbon mechanism bracket positioned centrally thereof and extending outwardly therefrom.
6. In a frame construction for typewriters, a frame member comprising a flanged plate having integral therewith two wings bendable into substantially parallel relation to each other, said plate being provided with a spring barrel bracket positioned rearwardly thereof.
7. In a frame construction for typewriters, a frame member comprising a flanged plate having integral therewith two wings bendable into substantially parallel relation to each other, said plate being provided with a spring barrel bracket and said bracket having an integral rod guide.
8. In a frame construction for typewriters, a frame member comprising a flanged plate having integral therewith two wings bendable into substantially parallel relation to each other, said plate being provided with integral ribbon mechanism brackets extending rearwardly thereof.
9. In a frame construction for typewriters, a frame member comprising a flanged plate having integral therewith two wings bendable into substantially parallel relation to each other, said plate being provided with integral space key brackets extending forwardly thereof.
10. In a frame construction for typewriters, a flanged frame member formed by a metal stamping comprising a back plate and two side wings integral therewith, said side wings being provided with lugs, combined with a front plate positioned across the front ends of the side wings and fastened to said lugs, said front plate being provided in its lower edge with guides for the key levers.
11. In a frame construction for typewriters, a flanged frame member formed by a metal stamping comprising a back plate and two side wings integral therewith, combined with a vertical front plate extending between the side wings and attached thereto, said front plate being provided with a stepped and notched upper edge for the reception of brackets adapted to support certain parts of the key action.
12. In a frame construction for typewriters, a flanged frame member formed by a metal stamping comprising a back plate and two side wings integral therewith, combined with an exterior frame within which is positioned the frame member formed by said metal stamping, and a vertical front plate positioned across the space intervening the side wings of said frame member, the end portions of said front plate being attached to the exterior frame.
13. In a frame construction for typewriters, a flanged frame member formed by a metal stamping comprising a back plate and two side wings integral therewith, combined with an exterior frame within which is positioned the frame member formed by said metal stamping, means for attaching the interior frame member to the exterior frame, and a vertical front plate fastened to the side wings of said interior frame member at the forward ends thereof, the end portions of said front plate being attached to the exterior frame.
14. In a frame construction for typewriters, the combination with a frame member provided with side plates, of a front plate attached to said side plates, said front plate being notched at its top edge and slotted in the lower edge thereof, said notches in the top edge being adapted to receive brackets for certain levers of the key action and the slots in the lower edge being adapted to serve as guides for key levers.
15. In a frame construction for typewriters, a front plate for an interior frame provided near its lower edge with an offset, said lower edge being slotted, and said slots being adapted to serve as guides for key levers of the key action.
16. In a typewriter, the combination with an exterior frame, of an interior frame separate from the exterior frame and attached thereto, a front plate attached to said interior frame, and a sector positioned in the rear of the front plate for carrying means adapted to support key levers, said sector comprising a metal plate provided with arcuate edges and with marginal flanges extending at a right angle to said body of the plate, said flanges operating to stiffen the plate and to preclude distortion thereof.
17. In a typewriter, the combination with an exterior frame, of an interior frame separate from the exterior frame and attached thereto, a front plate attached to said interior frame, and a sector the end portions of which are fastened to the interior frame, said front plate having means for guiding key levers and said sector being adapted to support said key levers.

18. In a frame construction for typewriters, a sector comprising a metal plate stamped with arcuate edges the end portions of said plate being bent to produce attaching flanges extending crosswise of the plate and the marginal edges of said plate being bent to produce flanges extending between said transverse attaching flanges.
19. In a frame construction for typewriters, a sector composed of a stamped and flanged plate, said plate being provided with a fastening lug at the middle of one edge thereof.
20. In a typewriter, the combination of an exterior frame, an interior frame positioned within said exterior frame and attached thereto, said interior frame being provided with means for carrying a substantially large number of the working parts of the typewriter, and a front plate attached to the forward part of said interior frame, said exterior frame extending forwardly of the front plate.
- In testimony whereof I have signed my name to this specification in the presence of 25 two subscribing witnesses.
